UNITED STATES PATENT OFFICE.

WILLIAM T. HANNA, OF CINCINNATI, OHIO.

LOCOMOTIVE STOKER.

Application filed April 28, 1920. Serial No. 377,336.

To all whom it may concern:

Be it known that I, WILLIAM T. HANNA, a citizen of the United States of America, and a resident of Cincinnati, in the county 5 of Hamilton and State of Ohio, have invented a new and useful Improvement in Locomotive Stokers, of which the following is a specification.

An object of my invention is to provide 10 a stoker, in which the fuel is to be placed manually at the furnace opening and within the furnace door, and is to be thence automatically carried and distributed uniformly over the bed of coals by blasts of steam or 15 of air.

Another object of my invention is a means for synchronizing the movement of the furnace door, and of the blasts of steam or air.

These and other objects are attained by 20 the means described in the specification and illustrated in the accompanying drawings, in which:—

Fig. 1 is front elevation of a locomotive stoker embodying my invention.

Fig. 2 is a view on line 2—2 of Fig. 1.

Fig. 3, is a sectional view taken upon line 3—3 of Fig. 2.

Fig. 4, is a detail sectional view of the 30 engine for actuating the doors and taken upon line 4—4 of Fig. 1.

Fig. 5, is a vertical sectional view taken upon line 5—5 of Fig. 4.

Fig. 6, is a front elevation of a modified 35 form of my invention.

Fig. 7, is a plan view of the parts shown in Fig. 6, the dotted lines showing the relative position of the parts when the door is open.

Fig. 8 is an elevation showing a modified 40 form of stoker embodying my invention.

Fig. 9 is a side elevation of the device, viewed from the left, as shown in Fig. 1.

My invention is intended to be applied 45 particularly to locomotives of the switch engine type, and consists broadly of an ejector A which is located upon the lower wall of the fuel feed opening a, a blast controlling valve B, by means of which blasts of fluid under pressure are admitted to the ejector A, means for opening the furnace doors D, D', and levers for actuating the blast controlling valve, which are connected to the means for actuating the furnace doors, whereby when the furnace doors are opened 50 blasts of fluid under pressure are simultaneously released from the ejector.

In the preferred embodiment of my invention I locate a distributor plate a' upon the lower wall of the furnace door opening a. This distributor plate a' may be of the 60 form of the distributor plate C' which is illustrated in my United States Letters Patent No. 979,849. The ejector which is illustrated is of the steam ejector type and consists of a housing having an upper steam 65 chamber a² and a lower steam chamber a³, from each of which radiate a series of nozzles a⁴, a⁵. This housing has journal arms a⁶, a⁷, which are journaled upon the ends of steam pipes b, b', respectively, which are 70 connected by suitable piping with the ends of coupling b², which is connected to the housing of the blast controlling valve B. In this piping are located regulating valves b³, b⁴, respectively, by means of which the 75 amount of fluid admitted to the pipes b, b', respectively, may be regulated so that the pressure in the upper chamber a² may be made as much greater than the pressure in the chamber a³ as may be desired, so as to 80 get a stronger blast of steam from the upper set of nozzles a⁴ than from the lower set of nozzles a⁵. The degree of pressure in the respective pipings is shown by the indicators b⁵, b⁶ of a gauge, which is connected by pipes b⁷, b⁸ with the respective pipings leading to 85 the pipes b, b'.

Ejector A is journaled upon the arms a⁶ and a⁷ in order that it may be thrown about its pivotal mountings on arms a⁶ and a⁷ to an inoperative position in front of the firing opening a, and in the bottom of the door frame E, as shown in dotted lines in Fig. 2. In this position it is covered by the hinged plate e which is mounted upon pivots e', e² in the sides of the door frame E, as shown in Fig. 3. In the operative position of the ejector the plate e rests upon it as shown in full line in Fig. 2.

I will now describe the preferred means 90 for actuating the furnace doors, simultaneously with the release of steam from the ejector, as shown in Figs. 1 and 7.

The furnace doors D, D' are mounted 100 upon pivots d, d', which project from the walls of the furnace. The upper ends of the doors are provided with gear segments d², d³, which intermesh so that movement of one door effects a movement of the other door. Movement of door D is effected by an engine D⁴ by the following well known means. 105 The piston d⁵ of the engine is pivotally con- 110

ected to door D by means of a link d⁸. The pivotal mounting d⁶ of the link d⁵ on the door D is disposed above the pivot d supporting door D. Reciprocation of the 5 piston d⁴ in its cylinder is controlled by a sliding valve d⁷, which has a way d⁸ which may put the port d⁹ of the cylinder into communication either with the exhaust d¹⁰ or with the admission d¹¹. Slide valve d⁷ is connected by a link d¹² with the foot lever D², by means of which the slide valve d⁷ may be positioned to bring way d⁸ into communication with the fluid under pressure. A 10 spring d¹³ returns the slide valve d⁷ to normal position, putting the way d⁸ into communication with the exhaust d¹⁰ when the pressure on the foot lever D² is released. Link d¹² is connected by a series of links F with the valve stem B' of the blast controlling 15 valve B.

In operation when it is desired to place fresh fuel upon the coal, the stoker depresses the foot lever D². This simultaneously opens the furnace doors by means of the link d¹², depressing the slide valve d⁷ and placing the interior of the cylinder in communication with the fluid under pressure from the pipe d¹¹, and rotating the valve B' thru the series of links F to admit steam 20 to the pipes b, b', thence to the chambers a², a³ and to the ejector's nozzles a⁴, a⁵ to distribute the fuel over the bed of coals.

The upper and lower blasts are arranged so that in operation, when coal is fed in any 25 suitable manner to the front edge of the blast casing or ejector, the finer coal falls into the channels and is discharged as it comes within the range of the blasts from the lower nozzles. These lower nozzles are 30 generally discharging at a lower pressure. The larger lumps of coal ride down the ridges and as they drop from the ends thereof, come into the range of the upper blasts, which are essentially of greater pressure. 35 Thus by applying a comparatively powerful blast to the coarse coal, or lumps, and a comparatively weak blast to the finer coal or dust, a proper mingling and distribution of coal in the fire box is obtainable. This 40 arrangement also precludes the finer coal and dust to be blown up into the flue, thus saving a great portion of that fuel.

In Figs. 6 and 7 there is illustrated a modified form of door D³ which is provided 45 with the usual handle d¹⁴ for manual operation. Mounted upon one of the hinges of the door is a shaft d¹⁵ on which is mounted an arm d¹⁶ connected by means of a link d¹⁷ with a valve lever b¹⁰ which is secured 50 upon the valve stem of a blast controlling valve B², which is located upon the coupling b² in the same position that the valve B is located, in the form illustrated in Fig. 1. In the operation of this device the opening 55 of the door D³ rotates the shaft d¹⁵

about the pivot of the door and imparts a rotation to the valve stem of the valve B² to open the valve to admit steam to the steam ejector A. The closing of the door D³ closes the valve B² and shuts off the supply of steam to the ejector. 70

In Fig. 8 I have shown my invention combined with a locomotive stoker which is supplied with a means for automatically feeding fuel from a locomotive tender to a distributing plate such as the plate a'. Experience demonstrates that the part of an automatic stoker which is most apt to get out of order, is the automatic means for feeding the fuel from the tender to the fire door opening. By combining my invention with this automatic stoker, I have supplied means whereby my semi-automatic stoker may readily be substituted for the automatic stoker, in case of such breakdowns. 80

Referring to Fig. 8, G illustrates a feed tube for directing fuel into the housing E which surrounds the fire door opening, whence the fuel is distributed by gravity upon the distributor plate a'. The means for feeding the fuel to the feed tube G and of carrying it to the distributing plate a' form no part of the present invention and may be such as illustrated in my pending application Serial Number 308,851, and in 95 my Patent No. 1,445,275.

In stokers of this type, steam is fed continuously to the blast chamber, such as the chamber a², a³. To provide means for supplying a continuous blast of steam, I place a by-pass H in the steam admission pipe, to carry steam around valve B, and place in the by-pass a valve h by means of which steam may be cut off from the by-pass, when the valve B² is opened to admit steam thru 100 the valve B. 105

In operation to put the automatic stoker into commission, the valve B² is closed and the valve h is opened, thus steam is admitted continuously to the blast chamber so 110 that the automatic stoker is operated in the usual way.

Should the automatic stoker get out of commission, because of some derangement in the automatic fuel feeder, the valve B² 115 is opened and the valve h is closed. Then the operation of the semi-automatic stoker is the same as that heretofore described.

What I claim is:—

1. In combination with a furnace having a fuel feed opening, an ejector located at the fuel feed opening, a furnace door adapted to open and close the fuel feed opening, means for simultaneously operating the door and admitting fluid to the ejector, means for directing fuel in front of the ejector, and a regulated means comprising a by-pass for admitting a constant flow of fluid to the ejector. 120
2. In a locomotive stoker the combination 125

130

- of a furnace having a firing opening, an ejector in the bottom of the firing opening, a fuel shelf in front of the ejector, a fuel conduit adapted to direct fuel to the fuel shelf, a door for the firing opening, a pipe for conveying fluid under pressure to the ejector, a valve in the pipe, means for simultaneously opening the door and the valve, and a controllable means for directing fluid under pressure to the ejector independently of the valve. 45
3. In a stoker mechanism the combination of a furnace having a firing opening, a pivotally mounted plate adjacent the firing opening, a pivotally mounted ejector adapted to assume an operative position such that fuel delivered to the plate may be directed to the ejector, and an inoperative position wherein the plate precludes access 50 of fuel to the ejector, a door for the firing opening, means for conveying fluid under pressure to the ejector, a valve controlling the flow of fluid through the fluid conveying means, and an additional means for simultaneously operating the door, and controlling the flow of fluid through the fluid conveying means. 55
4. In a stoker mechanism the combination of a furnace having a firing opening, a door for said opening, a fuel shelf within the opening, a fuel conduit adapted to direct fuel to the fuel shelf, an ejector adapted to direct blasts of steam across said shelf, a steam supply pipe connected to said ejector, a regulating valve, a by-pass in the supply pipe and around the regulating valve, a valve in the by-pass, and means for simultaneously operating the door and regulating valve. 60
5. In a mechanical stoker the combination of a furnace having a fuel feed opening, a casing surrounding the fuel feed opening, an ejector for fluid under pressure pivoted to the casing and adapted to be swung to an operative position within the fuel feed opening or to an inoperative position in the casing, and a plate for directing the fuel to the ejector when in an operative position, and for covering and protecting the ejector from fuel when in an inoperative position. 65
6. In a mechanical stoker the combination of a furnace having a fuel feed opening, an ejector located within the fuel feed opening, means for supplying fluid under pressure to the ejector for feeding fuel to the furnace, a control valve for said means, doors adapted to open and close the fuel feed opening, an engine adapted to actuate the doors, an operating lever, and links connecting the operating lever with the control valve and with the engine for the doors. 70
7. In a locomotive stoker the combination of a furnace having a fuel feed opening, an ejector casing having two sets of chambers 65 provided with discharge openings for fluid under pressure, a pipe leading to one of the chambers and forming one of the journals for the ejector casing, a second pipe leading to the other chamber and forming 75 a second journal for the ejector casing, whereby the ejector may be moved to and from operative positions, and pipes for fluid under pressure adjacent to the fuel feed opening and connected to the respective journals of the ejector casing.
- In witness whereof, I have hereunto subscribed my name this 21st day of April, 1920.
- WILLIAM T. HANNA.
